US0D1028510S

(12) United States Design Patent (10) Patent No.: US D1,028,510 S
(45) Date of Patent: * May 28, 2024

(54) RIDE-ON LUGGAGE CASE

(71) Applicant: Ningbo Port Zhongdi Luggage Manufacturing Limited, Zhejiang (CN)

(72) Inventor: Weiliang Lin, Zhejiang (CN)

(73) Assignee: Ningbo Port Zhongdi Luggage Manufacturing Limited, Ningbo (CN)

() Term: 15 Years

(21) Appl. No.: 29/916,868

(22) Filed: Nov. 16, 2023

(51) LOC (14) Cl. 03-01

(52) U.S. Cl.

USPC D3/273; D3/279

(57) CLAIM

The ornamental design for a ride-on luggage case, as shown and described.

DESCRIPTION

FIG. 1 is a perspective view of a ride-on luggage case showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the ride-on luggage case that form no part of the claimed design.

1 Claim, 8 Drawing Sheets
